UNITED STATES PATENT OFFICE.

ARTHUR W. WELLINGTON, OF WATERBURY, CONNECTICUT, ASSIGNOR TO THE CHASE COMPANIES, INC., OF WATERBURY, CONNECTICUT, A CORPORATION.

FLASHLIGHT OR BATTERY HAND-LAMP.

1,377,646.

Specification of Letters Patent.

Patented May 10, 1921.

Application filed August 26, 1919. Serial No. 319,885.

To all whom it may concern:

Be it known that I, ARTHUR W. WELLINGTON, a citizen of the United States, residing at Waterbury, in the county of New Haven 5 and State of Connecticut, have invented a new and useful Improvement in Flashlights or Battery Hand-Lamps; and I do hereby declare the following, when taken in connection with the accompanying drawings 10 and the characters of reference marked thereon, to be a full, clear, and exact description of the same, and which said drawings constitute part of this application, and represent, in—

15 Figure 1 a view partly in side elevation and partly in central longitudinal section of a flashlight or battery hand-lamp constructed in accordance with my invention.

20 Fig. 2 a detached view in central longitudinal section of the battery-case from which everything has been removed except its terminal-strips and contact-button fixture which latter is shown by broken lines.

25 Fig. 3 a detached view of the insulating strip employed to insulate the lower terminal-strip from the lower rivet of the contact-button fixture housing.

30 Fig. 4 an enlarged broken sectional view showing the fastening-rivet of the lower end of the lower terminal-strip as sunk below the face of the case so as to clear the flange of the bottom-cap.

35 My invention relates to an improvement in that class of flashlights or battery hand-lamps which are constructed so as to prevent short-circuiting and the consequent wearing out of the batteries in case the lamp is placed in a wire mail-basket or brought 40 into contact with metal in such a way as to cause short-circuiting, the object being to produce a convenient and reliable lamp of the character described, with particular reference to reduction in the number of parts employed, and to cheapness of construction.

45 With these ends in view, my invention consists in certain details of construction as will be hereinafter described and pointed out in the claim.

50 In carrying out my invention as herein shown, the lower terminal-strip 2 leading from the contact-rivet 3 to the battery-spring 4 and hence to the lower pole of the battery 5 within the tubular fiber case 6, is insulated by a co-extensive insulating strip 55 7 from the lower housing-rivet 8 of the hous-

ing 9 of the contact-button fixture which is arranged in line with the said case and secured to the exterior surface thereof by the rivet 8 aforesaid, and by rivets 11, 11, which pass through laterally offsetting ears 12 of 60 the housing with which they do not aline as does the rivet 8 aforesaid.

The battery-case 6 in which the said rivets are mounted, is of insulating material, but it still becomes necessary to insulate the 65 lower terminal-strip 2 from the lower housing-rivet 8 under which the strip 2 passes on its way, so to speak, to the lower end of the battery-case.

To eliminate the threaded metal collars 70 ordinarily mounted at the respective ends of the case 6, I form external rolled in or cut screw threads 13 at the upper end thereof, and correspondingly rolled in or cut external threads 14 at the lower end thereof, the 75 upper threads 13 providing for the direct application to the case of the lens-ring 15 which holds the lens 16 in place, while the threads 14 provide for the direct application to the lower end of the case 80 of the bottom-cap 17, which receives a disk 18 of insulating material for the insulation from it of the battery-spring 4 which is hinged to the lower end of the terminal-strip 2, formed with a knuckle 19 for 85 such pivotal attachment. When the battery and cap are in place the said spring is interposed between them as shown in Fig. 2 and connects the battery with the contact-rivet 3 through the insulated terminal-strip 2. 90 The lower ends of the strips 2 and 7 are fastened to the lower end of the case 6 by a rivet 20 the outer end of which is kept out of contact with, and hence insulated from the flange of the bottom-cap 17. For this 95 purpose the said rivet 20 is located in a recess 21 in the threaded portion 14 of the battery case 6 as clearly shown in Fig. 4, whereby its outer end is sunk below the surface of the case so as to avoid contact with 100 the flange of the cap.

Otherwise than as described, my improved flashlight or battery hand-lamp may be of any approved standard construction. As shown it has a lamp 22 inclosed by, and in 105 circuit with a reflector 23 to which the upper terminal-strip 24 leads from one of the two offsetting rivets 11 of the housing 9. The contact-button fixture may also be of any standard construction. As herein shown, 110

it is provided with a sliding button 25, a push button 26, and a contact-spring 27 which latter coacts with the contact-rivet 3. The upper pole of the battery 5 is held 5 against the lamp 22 by the action of the battery spring 4.

By the use of the insulating strip 7, and the depressed rivet 20, I avoid the short-circuiting of the battery 5 through its lower 10 terminal strip 2. On the other hand, by producing the screw threads 13 and 14 directly in the ends of the battery-case 6 for the application of the lens-ring 15 and the bottom-cap 17, I simplify the question of insulation 15 and also dispense with the use of the threaded metal ferrules or rings heretofore employed at these points, and thus save expense and lighten the device.

I claim:—

20 A flashlight or battery hand-lamp having a tubular case provided with external screw threads formed directly in it at its lower end, a contact-button housing arranged in

line with the case and riveted thereto, a contact-rivet mounted in the case at a point 25 within the upper end of the said housing, a terminal-strip arranged in line with the housing and extending from the said contact-rivet to the lower end of the case, a bottom-cap for the case applied directly to 30 the exterior threads formed in the lower end thereof, and a rivet for fastening the lower end of the terminal strip to the lower end of the case, the outer end of the said rivet being located in a recess formed in the 35 threaded portion of the case, whereby the rivet is insulated from the flange of the said cap.

In testimony whereof I have signed this specification in the presence of two subscribing witnesses.

ARTHUR W. WELLINGTON.
